(57)

CLAIM

The ornamental design for a container and lid assembly for a breast pump, as shown and described.

DESCRIPTION

FIG. 1 is a front perspective view of a container and lid assembly for a breast pump;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The broken lines in the drawings illustrate portions of the container and lid assembly for a breast pump and form no part of the claimed design.

1 Claim, 5 Drawing Sheets
